THROAT PLATE FOR OVEREDGE SEWING MACHINE

John M. Washburn, Hartford, Conn., assignor to The Merrow Machine Company, Hartford, Conn., a corporation of Connecticut

Filed Sept. 6, 1961, Ser. No. 136,265

5 Claims. (Cl. 112—260)

This invention relates to throat plates employed in overedge sewing machines, and more particularly to an improved stitch finger assembly for overedge machines employing two needles in side by side relationship.

In the formation of certain types of seams, two rows of needle thread loops are placed in the work material along lines parallel to the work material edge and a third thread is manipulated by the looper mechanism of the machine to be interlooped with both series of needle thread loops. To accomplish this operation, in certain seams it is necessary that the machine be provided with two stitch fingers, one of which extends between the two rows of needle thread loops. In the formation of the seam, the needle which forms the row of loops remote from the work material edge carries its thread downwardly through the fabric to a point below the lower edge of the last mentioned stitch finger into operative relationship with the looper which carries the loop laterally beneath the stitch finger. As the material is fed through the machine, the loop slides longitudinally along the stitch finger until it slips off the distal end of the finger.

In many types of seams, the lateral spacing between the two rows of needle thread loops is quite small, and since the inner stitch finger must project between the two rows of loops while permitting clearance so that the needles can pass down on opposite sides of the stitch finger, the finger must, of necessity be of relatively small width. At the same time, because of the high speed of feed, the stitch finger must have a reasonable length, thus resulting in a requirement that the stitch finger be relatively long, thin and cantilevered from the throat plate in order that the stitches may slip freely from its distal end. During the formation of the stitches, the needle thread loops are drawn taut while they are still on the stitch finger. This action exerts a pull on the stitch finger which, because of the design requirements referred to above, subjects the finger to vibration when in use. Thus, the stitch finger, because of its dimensions, is readily subjected to damage and, if formed integrally with the throat plate, is a primary cause of damage requiring replacement of the complete throat plate. Previous efforts to provide throat plate construction in which the stitch finger may be replaced without discarding the entire plate have not proved completely satisfactory because of difficulties encountered in providing satisfactory means for securing the finger on the plate with sufficient rigidity to resist the tendency of the finger to vibrate when the machine is operated.

Accordingly, it is an object of the present invention to provide a throat plate for use in a two-needle overedge sewing machine having a replaceable stitch finger which may be rigidly secured to the throat plate.

In the achievement of the foregoing, and other objects, a throat plate assembly is constructed with an upwardly opening groove of uniform width and varying depth formed in the upper surface of the plate. The inner stitch finger is separately formed from sheet material having a thickness which provides a sliding fit between the sidewalls of the groove in the throat plate. At one end, the stitch finger is formed with a finger portion having a maximum thickness at its base substantially equal to the thickness of the throat plate and tapering toward the distal or free end of the finger to permit thread loops

2

to slide easily from the finger portion. The opposite end portion of the stitch finger is formed as a shank or tang whose vertical dimension is somewhat less than the depth of the groove in the throat plate. The groove in the throat plate is formed with a flat bottom portion which extends from the inner end of the needle receiving slot within which the stitch finger is located lengthwise of the throat plate to terminate at one end of a depressed intermediate bottom portion of the throat plate groove. The configuration of the stitch finger and bottom portion of the groove is such that when its tang is initially placed in the groove, the lower surface of the tang contacts the groove only at two points, one at the forward end of the flat portion adjacent the inner end of the needle receiving slot and the other point of contact being near the end of the depressed intermediate portion of the groove remote from the flat portion. At a location longitudinally of the slot substantially midway between the inner end of the flat portion and this latter point of contact, a bore extends through the body of the throat plate transversely across the slot. A wedging pin having a tapered wedge section is received within this bore and its tapered portion is adapted to engage a notch in the upper surface of the tang so that when the pin is driven laterally across the slot, the tapered portion of the pin forces the tang portion downwardly and rearwardly within the groove to seat the forward end of the tang portion in face to face contact with the flat portion, thereby resiliently locking the stitch finger in position upon the plate. The lower portion of the base of the finger portion of the stitch finger is formed with an upwardly and forwardly inclined shoulder surface which extends upwardly from the lower side of the stitch finger and is hooked over the edge surface of the throat plate at the inner end of the slot. The rearward and downward wedging action exerted on the stitch finger tang by the wedge pin tends to move this shoulder toward engagement with the opposed surface of the throat plate, thus exerting a firm longitudinal locking action on the stitch finger. The downward flexing action flexes the relatively large vertical depth of the stitch finger which serves to increase the rigidity of the finger when the machine is in operation.

Other objects and features of the invention will become apparent by reference to the following specification taken in conjunction with the accompanying drawings.

In the drawings:

FIG. 1 is a partial top plan view of a throat plate embodying the invention;

FIG. 2 is a cross-sectional view of the assembly of FIG. 1 taken on the line 2—2 of FIG. 1;

FIG. 3 is a cross-sectional view taken on the line x—x of FIG. 1, showing the assembly without the removable stitch finger or wedging pin;

FIG. 4 is a cross-sectional view similar to FIG. 3 showing the removable stitch finger in place within its receiving groove prior to the placement of the wedging pin; and

FIG. 5 is a cross-sectional view similar to FIG. 3 showing the parts in their assembled relationship.

Referring first to FIG. 1, there is shown a throat plate designated generally 10 formed with a feed dog receiving opening 12 and a relieved feed dog receiving recess 14 which accommodate motion of the feed dogs of the machine in a well known manner to feed work material indicated in broken line at W through the machine in the direction indicated by arrow 16. Throat plate 10 is bored as at 18 to receive a screw which is employed to mount the plate upon the machine in the general fashion indicated in my prior Patent No. 2,233,088, granted February 25, 1941, to which reference may also be had for the general relationship of throat plate 10 in an overedge sewing machine.

Immediately to the rear (the terms "front" and "rear" refer to the direction of feed, the direction of feed moving the work material from front to rear) a first stitch finger 20 is formed as an integral part of throat plate 10. The inner edge 22 of stitch finger 20 is located in spaced parallel relationship to a side edge 24 on throat plate 10, edges 22 and 24 defining the longitudinal sidewalls of a needle receiving slot whose inner end is defined by a transversely extending edge 26 on throat plate 10. The transverse width of the needle receiving slot is such that thread carrying needles of an overedge sewing machine upon which the throat plate is employed pass vertically through the slot at locations indicated in FIG. 1 at 28 and 30.

A groove designated generally 32 is formed in the upper surface of throat plate 10 and, as best seen in FIG. 1, extends substantially entirely across the upper surface of throat plate 10 from transverse edge 26 in longitudinal alignment with the longitudinal center line of the needle receiving slot. Groove 32 is of uniform width and has spaced parallel vertical sidewalls.

The configuration of the lower wall of groove 32 is best seen in FIGS. 3 through 5. At the end of groove 32 adjacent to transverse edge 26, the lower wall of groove 32 is formed with a flat downwardly and inwardly inclined portion 34. At its inner end, flat portion 34 terminates at one end of an intermediate portion 36 which, since it defines the maximum depth of the groove 32 relative to the upper surface of throat plate 10, will be referred to as a depressed portion. Throat plate 10 is formed with a transverse bore 38 which, as best seen in FIGS. 1 and 2, extends from the sidewall 40 of throat plate 10 transversely across groove 32 to open into feed dog opening 12. Preferably, for reasons discussed below, bore 38 is extended to similarly pass through that portion of throat plate 10 on the opposite side of feed dog opening 12 as at 42.

Groove 32 and bore 38 are formed in throat plate 10 for the purpose of locating and securing a stitch finger element designated generally 44 in position upon the throat plate. Stitch finger element 44 is constructed from plate or sheet material having a thickness adapted to be snugly received between the vertical sidewalls of groove 32 and is formed at one end with a stitch finger portion 46, the remaining portion (right hand portion as viewed in FIGS. 4 and 5) being formed as an elongate tang 48.

Stitch finger element 44 has its maximum vertical dimension or depth at the base of finger portion 46, at which point the depth of finger element 44 is substantially equal to the vertical thickness of throat plate 10. Since groove 32 extends downwardly only partially through throat plate 10, the base of finger portion 44 is defined in part by an upwardly and forwardly inclined shoulder 50 which extends upwardly from the tapered lower edge 52 of finger portion 46 to merge through a smooth curve into the flat lower edge 54 of tang portion 48. The upward and forward taper of lower edge 52 of finger portion 46 facilitates the smooth sliding of thread loops along the stitch finger in the direction of work material feed (to the left as viewed in FIGS. 4 and 5) until the thread loops slip from the stitch finger at its distal end 56.

As best seen in FIG. 4, the shape of the lower edge of stitch finger element 44 is such that when the element is placed in groove 32, tang portion 48 contacts the lower wall of groove 32 only at two points, one point 58 being located near the outer end of flat portion 34 and the other point of contact 60 being between the extreme end of tang portion 48 and a location adjacent the end of depressed portion 36 remote from flat portion 34. Between the two points of contact 58 and 60, the lower edge 54 of tang 48 is vertically spaced above lower wall 34—36 of groove 32.

Stitch finger element 44 is assembled to throat plate 10 by first placing tang portion 48 in groove 32 and

sliding element 44 to the right as viewed in FIG. 4 until shoulder 50 contacts the lower portion 62 of transverse edge 26 of the throat plate. Lower portion 62 of edge 26 is inclined upwardly and forwardly at a slightly greater angle than shoulder 50. A notch 64 is cut into the upper edge of tang portion 48 at a location such that when shoulder 50 contacts edge 62, notch 64 is disposed longitudinally within groove 32 in alignment with bore 38.

A wedge pin 66 is received within bore 38 with a loose drive fit. The inner end of pin 66 is tapered as at 68 (FIG. 2) so that as pin 66 is driven into bore 38 from right to left as viewed in FIG. 2, tapered portion 68 passes through notch 64 and enters that portion of bore 38 to the left of groove 32 as viewed in FIG. 2. Further driving movement of pin 66 to the left as viewed in FIG. 3, causes tapered portion 68 of the pin to flex tang portion 48 downwardly toward the lower wall of groove 32. Tang 48 is tempered to permit the tang to flex under the wedging action of pin 66 and the pin is driven into bore 38 until lower edge 54 of tang 48 is flexed downwardly to contact flat portion 34 of groove 32 throughout the length of the flat portion. The downward flexing of tang 48 flexes finger portion 46 upwardly from the FIG. 4 position until its upper edge 70 is moved into substantial parallelism with the upper surface of stitch finger 20. The maximum depth of notch 64 is located somewhat to the left of the center of bore 38 as viewed in FIGS. 4 and 5 and hence the wedging action of tapered portion 68 of pin 66 is also applied against the inclined right hand portion of notch 64 to urge stitch finger element 44 to the left at the same time that tang portion 48 is flexed downwardly by the pin. This action thus also resiliently wedges shoulder 50 toward lower edge portion 62 of transverse edge 26.

The foregoing construction achieves a central or inner stitch finger on throat plate 10 which is held in position extremely rigidly by virtue of the wedging action of pin 66. The application of the wedging force to urge shoulder 50 tightly against edge 62 firmly locks the stitch finger element against longitudinal movement within the slot and the provision of the shoulder at the same time permits the vertical thickness or depth of the finger portion 46 to be made relatively large to further increase the rigidity of the operative portion of the stitch finger. Stitch finger element 44 may be readily removed by inserting a drive pin through bore 42 to drive pin 66 out of bore 38.

While one embodiment of the invention has been described in detail, it will be apparent to those skilled in the art that the disclosed embodiment may be modified. Therefore, the foregoing description is to be considered exemplary rather than limiting and the true scope of the invention is that defined in the following claims.

What is claimed is:

1. For use in an overedge sewing machine; a throat plate having a first stitch finger thereon defining an elongate needle receiving slot having spaced longitudinal side edges and a transverse edge defining the inner end of said slot, said plate having an upwardly opening groove therein extending from said transverse edge across the upper side of said plate, an elongate plate-like second stitch finger member having a stitch finger portion at one end and an elongate tang, said tang being adapted to be received within said groove with the opposed sides of said tang engaged with the side surfaces of said groove to locate said finger portion in a central longitudinally extending position within said slot, the lower surface of said groove having an intermediate portion thereof depressed relative to the opposed lower surface of said tang, a shoulder on said member engageable with said transverse edge, and wedge means engageable between said plate and the upper surface of said tang at a location above said depressed portion of said groove for flexing said tang portion downwardly within said groove to resiliently lock said second stitch finger member to said plate.

2. For use in an overedge sewing machine; a throat plate having a first stitch finger thereon defining an elongate needle receiving slot having spaced parallel longitudinal side edges and a transverse edge defining the inner end of said slot, said plate having an upwardly opening groove therein extending from said transverse edge across the upper side of said plate in alignment with the longitudinal center line of said slot, an elongate plate-like second stitch finger member having a thickness substantially equal to the transverse width of said groove in said plate, a stitch finger portion at one end of said second stitch finger member, a tang integral with said stitch finger portion and adapted to be received on edge within said groove to locate said stitch finger portion centrally within said slot, a downwardly projecting shoulder on the lower side of said second stitch finger member engageable with said transverse edge of said slot to longitudinally locate said stitch finger portion within said slot, the lower surface of said groove having an intermediate portion thereof depressed relative to the opposed lower edge surface of said tang, and wedge means engageable between said plate and the upper edge surface of said tang portion above said depressed intermediate portion of said groove for flexing said tang portion downwardly within said groove and urging said shoulder against said transverse edge to lock said second stitch finger member to said throat plate.

3. A throat plate as defined in claim 2 wherein said wedge means comprises a wedge pin, said throat plate having a bore therethrough extending transversely across said groove and receiving said wedge pin, the upper surface of said tang having a notch therein adapted to engage said wedge pin to depress said tang portion and to urge said shoulder against said transverse edge upon sliding movement of said pin transversely across said groove.

4. A throat plate as defined in claim 2 wherein the lower surface of said groove includes a flat portion extending between said depressed portion and said transverse edge, the lower surface of said tang being flat and

adapted to engage said flat portion at a point adjacent said transverse edge and to engage the lower surface of said groove at the side of said depressed portion remote from said flat portion when said wedge means is disengaged therefrom, said wedge means being operable to flex said tang portion downwardly within said groove until the lower edge of said tang is in face to face contact with said flat portion of said groove throughout the length of said flat portion.

5. For use in an overedge sewing machine; a throat plate having a first stitch finger thereon defining an elongate needle receiving slot open at one end and having spaced longitudinal side edges and a transverse edge defining the inner end of said slot, said plate having a groove therein extending from said transverse edge lengthwise on one side of said plate, an elongate plate-like second stitch finger member having a stitch finger portion at one end and an elongate tang, said tang being adapted to be received within said groove with the opposed sides of said tang engaged with the side surfaces of said groove to locate said finger portion in a central longitudinally extending position within said slot, the bottom surface of said groove having an intermediate portion thereof depressed relative to the opposed surface of said tang, a shoulder on said stitch finger member engageable with said transverse edge, and means slideably received within said plate and engageable with said tang at a location opposed to said bottom portion of said groove for flexing said tang portion in a direction within said groove to resiliently lock said second stitch finger member to said plate.
